(57) **CLAIM**

The ornamental design for a voting terminal, as shown and described.

DESCRIPTION

FIG. 1 is a front perspective view of a voting terminal showing our new design;

FIG. 2 is a front elevation view thereof;

FIG. 3 is a left side elevation view thereof;

FIG. 4 is a top plan view thereof; and,

FIG. 5 is a front elevation view of the voting terminal with the doors in a closed storage position.

The stand shown in broken lines and described is for illustrative purposes only and forms no part of the claimed design.
